UNITED STATES PATENT OFFICE

JULIEN BERGÉ, OF TIRLEMONT, BELGIUM, ASSIGNOR TO RAFFINERIE TIRLEMONTOISE,
SOCIÉTÉ ANONYME, OF TIRLEMONT, BELGIUM, A CORPORATION

PROCESS FOR THE PRELIMINARY TREATMENT OF RAW SUGAR AND THE LIKE

No Drawing. Application filed March 15, 1930, Serial No. 436,255, and in Germany August 26, 1926.

This invention pertains generally to the formation of crystals from solutions. I shall describe the same in connection with the manufacture of sugar as an example. However, it is understood that it is applicable to a large variety of other products.

The invention is applicable to the enhancing of the yield from massecuite, especially after the massecuite has been subjected to the ordinary centrifuging heretofore employed to furnish the product known in commerce as raw sugar, and to the delivery of such increased yield to the refinery in a highly purified state.

Raw sugar is generally found in commerce containing all the way from 85 to 95 or 96% more or less of crystallized sugar, the rest constituting non-sugar elements such as invert sugars, gums, ash, etc. and water. These non-sugar elements form a syrup which coats the individual sugar crystals and contaminates the product. This syrup, of course, is a part of the mother syrup in which the sugar crystals were formed. If the raw sugar has been manufactured in temperate climates, or has been stored in damp places, or subjected to moisture in transportation, or otherwise, the water content of the adhering syrup is such as to hold in solution a considerable amount of sucrose or crystallizable sugar such as to raise the sugar content of the adhering syrup above the approximate minimum to which it is ordinarily practicable to crystallize sugar from mother syrup. In ordinary practice when this syrup is removed from the crystals it is necessary to reprocess the same in order to extract therefrom this excess sugar. This, of course, consumes considerable time, is laborious and expensive, and results in sugar losses.

On the other hand if the raw sugar has been produced in hot, dry climates, or is otherwise rapidly dried, the syrup adhering to the crystals has given up more water than is required to hold the same in solution, and thus forms a sort of lacquer around the sugar crystals. This so-called lacquer contains considerable sugar which would otherwise be crystallizable except for the rapid drying. The sugar content of this dried syrup or so-called

lacquer, is, therefore, also higher than the approximate minimum to which it is ordinarily practicable to impoverish mother syrup.

The removal of either this so-called lacquer, or the first mentioned crystal coating syrup, from the sugar crystals has required operations such as washing with water or steam or with syrups, such as highly purified syrups or syrups of various stages of purity, etc. All washing mediums carry away in solution a portion of the crystallized sugar, thus further reducing the yield, and making necessary further processing directed toward the recovery of such sugar losses.

The removal of substantially all of the adhering syrup is highly desirable before beginning refining operations, among other things, not only because the syrup discolors the sugar crystals, but because the removal of as much of the ash as possible provides a high saline co-efficient; that is a high ratio of sugar to the salts contained in the mass to be refined. In beet sugar manufacture, for instance, when the mother liquor of the refinery has been impoverished to the extent that its sugar divided by its ash is approximately equal to 5, more or less, it has generally been considered impracticable to attempt to further reduce the sugar content of the mother liquor by the ordinary sugar boiling methods.

The presence of invert sugars also presents crystallization difficulties. This offers an additional reason for desiring to remove as much as possible of the adhering syrup from the raw sugar before beginning refining operations.

The centrifugals used heretofore operate at a speed such that the centrifugal force generated is sufficient to remove syrup from syrup, but leave a film of syrup adhering to the sugar crystals even though centrifuging takes place when the mass is relatively warm. The mass is ordinarily held at temperatures between 50° to 60° C. during centrifuging. These centrifugals exert a centrifugal force in the neighborhood of 500 to 600 times the weight of the mass. As above pointed out, washing operations are necessarily resorted to in order to remove

the remaining film of syrup from the crystals. This washing, of course, redissolves crystallized sugar and the result is that considerable portions of the crystallized sugar 5 are carried away in the washing fluids.

To obtain an increased crystallization of sugar from the adhering mother syrup, as well as to deliver such crystallized sugar to the refinery in a highly purified state, I subject the raw sugar to certain processes whereby the water content of the adhering syrup approaches a value at which such water content is substantially just sufficient to hold in solution, at a desired temperature, the non-sugar constituents of the syrup and the percentage of sugar that is to be left in the syrup. In other words, the water content of the syrup approaches the value at which it is substantially just sufficient to hold in 10 solution, at a desired temperature, the non-sugar constituents of the final molasses, and the percentage of sugar that is to be left in the molasses. It follows that the rest of the sugar in the syrup is available for crystallization, and such crystallization is materially aided by the presence of the very large number of sugar crystals onto which such sugar readily deposits. 15

The amount of sugar which is to be left in the molasses is determined by experience in the art, is more or less a function of the impurities present, and is generally a practicable irreducible minimum beyond which the labor, time and expense in trying to effect 20 further crystallization by the ordinary sugar boiling methods is not warranted by the small further yield thus obtained.

If the adhering syrup contains more than the desired amount of water, it is desiccated, 40 whereas if the adhering syrup contains less than the desired amount of water it is moistened sufficiently to bring it to the desired state. The moistening of the syrup frees the sugar formerly held fast in the lacquer-like coating, and makes such sugar available for crystallization. 45

The amount of water to be added or subtracted from a particular batch of raw sugar 50 may be ascertained upon an analysis of a sample, or empirical means may be devised for this purpose. For instance let us assume for the purpose of illustration that a sample of a batch of raw sugar is of the following 55 composition:

Polarization	95.
Water	2.26
Non-sugar	2.74

Let it be assumed that it is desirable to obtain a molasses having a purity equal to 60 62 and that centrifugal separation is to take place at a temperature of 20° centigrade. It is generally understood that at a temperature 65 of approximately 20° C. and a purity of 62,

one kilogram of water will dissolve 2.62 kilograms of sugar in addition to the non-sugar constituents. Tables for other temperatures and purities can be obtained or readily prepared. From this the following 70 is derived:

The purity of a syrup or molasses is equal to

$$100 \times \frac{\text{Non-crystallized sugar}}{\text{Non-crystallized sugar} + \text{non-sugar}} \quad 75$$

Substituting the data of the example under consideration we obtain

$$100 \times \frac{2.62}{2.62 + \text{non-sugar}} = 62 \quad 80$$

By transposing we obtain

$$\frac{100 \times 2.62}{62} = 2.62 + \text{non-sugar} \quad 85$$

Therefore the quantity of non-sugar in a molasses, having a purity of 62 and containing 2.62 kilograms of sugar, is as follows:

$$\text{Non-sugar} = \frac{100 \times 2.62}{62} \quad 90$$

$$- 2.62 = 4.23 - 2.62 = 1.61 \text{ kg.}$$

The concentration of non-sugar with respect to water, hereafter referred to as the concentration of non-sugar, is therefore equal to 95

$$\frac{\text{Non-sugar}}{\text{Water}} = \frac{1.61 \text{ kilograms}}{1 \text{ kilogram}} = 1.61$$

To obtain molasses having a purity of 62 100 when the centrifuging is to take place at approximately 20° C. the concentration of the non-sugar should be 1.61 according to this calculation.

Tables for other temperatures and purities 105 of molasses can be readily prepared.

The concentration of non-sugar in the sample of raw sugar above mentioned is as follows:

$$\text{Concentration of non-sugar} = \frac{\text{Non-sugar}}{\text{Water}} = \frac{2.74}{2.26} = 1.21 \quad 110$$

It is readily seen that the water content of the batch of raw sugar under consideration 115 must be reduced so that the concentration of non-sugar may approach 1.61.

If one kilogram is the quantity of water required in a quantity of syrup containing 1.61 kilograms of non-sugar in order that the 120 syrup may retain in solution sufficient sugar to have a purity of 62, the quantity of water required in a quantity of syrup containing 2.74 kilograms of non-sugar is

$$\frac{2.74}{1.61} = 1.70 \text{ kilograms of water.} \quad 125$$

It is, therefore, seen that from each 100 kilograms of raw sugar corresponding to the above sample, it is necessary to extract 130

2.26 - 1.70 = 0.56 kilograms of water. Upon the reduction of the water content by 0.56 kilograms the centesimal composition of the raw sugar is approximately as follows:

5 Polarization	95.535
Water	1.710
Non-Sugar	2.755

In checking the latter formula we find that 10 the concentration of non-sugar is as follows:

$$\frac{2.755}{1.71} = 1.61$$

15 which is the desired concentration.

The above example is given merely for 20 illustrative purposes and happens to be for a particular batch of beet raw sugar. The amount of water to be added or subtracted from any particular batch of raw sugar 25 whether beet, cane, or otherwise, in order to obtain molasses of any desired purity, can be either calculated, or empirically determined by persons skilled in the art and familiar with this invention.

25 It is to be understood, however, that all 30 calculations and empirical determinations are merely estimates and are subject to actual operating conditions. The characteristics of different batches of raw sugar vary, and, therefore, the exact amount of water to be 35 added or to be removed from the adhering syrup of a particular batch, to obtain molasses of the exact purity desired, may require actual trial accompanied by an analysis 40 of the final molasses. The water content of the adhering syrup is then raised or lowered in accordance with the invention herein disclosed.

Furthermore this invention is not limited 45 to optimum conditions, that is to the presence of the exact amount of water desired, but includes all desiccating and/or moistening of raw sugar to obtain an increased yield.

Many forms of apparatus may be used in 50 carrying out this process. For instance, the raw sugar may be placed in an ordinary storeroom in sacks. These sacks may be arranged in such a way as to permit more or less free circulation of air of the desired 55 moisture content between and around the sacks. Relatively dry or relatively moist air may then be circulated through the storeroom according to whether the water content of the adhering syrup is to be lowered or raised.

55 The temperature of the storeroom may be 60 regulated by regulating the temperature of the circulating air, or by entirely independent devices such as radiators, steam coils, etc. For instance, it might be desirable to hold the raw sugar at one temperature and circulate the air at another temperature, especially to bring about, or regulate the rate of, a change in the degree of saturation of the air coming in contact with the sugar. The storeroom may 65 be at the temperature at which centrifuging is

to take place, or may be at any other temperature, or series of temperatures, at the time of moistening or of desiccating of the syrup, and then may be brought to the desired centrifuging temperature at some time before 70 the centrifuging takes place. The regulation of moisture and temperature is somewhat a matter of choice to obtain conditions conducive to maximum crystallization. For instance, slow cooling with slow evaporation 75 of water is considered conducive to this end. In the case of moistening dry syrup the temperature and moisture content may if desired, be raised above that at which the sugar is to be centrifuged, and then lowered. However this is not necessary, and may not even be desirable in many instances.

80 Any means may be employed to determine when the moistening or desiccating should be stopped, such as taking samples for analysis 85 at desired intervals, etc. or automatic means may be devised for this purpose. Automatic means may also be devised for regulating the temperature of the storeroom. Any form of chamber or storeroom may be employed, 90 which is preferably, though not necessarily, closed. The sugar need not be in sacks, but may be in piles, spread out in layers, or may be in any other form or condition suitable for the results desired.

95 After the syrup has reached the desired state the raw sugar is centrifuged in centrifugals in which it is subjected to centrifugal forces much higher than heretofore employed. The centrifugals generally operate with 100 forces substantially between 1200 to 7000 (or more) times the weight of the mass centrifuged but may operate with a force as low as 800 as disclosed in my co-pending application Serial No. 167,598, which has resulted in Patent No. 1,775,385, and are capable of separating substantially all of the syrup from the sugar crystals, apparently without regard to ordinary temperatures and viscosities of the 110 syrup. The forces generated in these centrifugals overcome the adherence of the syrup for the sugar crystals, thus effecting a substantially complete separation of the former from the latter. Owing to the high centrifugal forces employed the sugar may be centrifuged at relatively low temperatures, that is, at temperatures much lower than heretofore employed, thus permitting an unusually high degree of crystallization. Centrifuging may take place at 20° C. or in many cases 115 at temperatures even lower. However, centrifuging may take place at other temperatures if desired.

120 Even though centrifuging in my process may take place at sub-normal temperatures, masses containing crystal flour of foam or both are satisfactorily handled, and the syrup thrown off contains very little crystal flour. This is a distinct improvement over the centrifuging heretofore practised in which 125 130

masses containing crystal flour or foam were very troublesome and could not be satisfactorily centrifuged even with excessive washing. In my process the foam disappears, a considerable portion of it finding its way toward the inner wall of the sugar. By crystal flour is meant sugar crystals under normal size and particularly very small crystals. This term is known in the art. In centrifuging masses or raw sugars containing crystal flour heretofore the crystal flour and syrup formed into ball-like masses from which the crystal flour could not be discharged. In my process such ball-like masses, if formed, are broken up by the extremely high centrifugal forces used, and the syrup is driven from the crystal flour.

Owing to the substantially complete crystallization of sugar from the syrup and the substantially complete separation of the molasses (exhausted syrup) from the crystallized sugar, an unusually high yield of raw sugar is delivered to the refinery. This sugar is in a high state of purification, thus permitting an unusually high degree of crystallization in the refining processes. In many instances the sugar is in such a highly purified state that for many purposes further refining is unnecessary.

It is, of course, understood that although the use of water, steam, syrup of high purity or syrup at various states of purity, etc. in the centrifugals to assist in the separation of the syrup is in most instances unnecessary, the same may be employed if desired. Ordinary run-off liquor from the centrifugals, in the event that washing is not resorted to, is molasses of substantially the desired sugar content.

In the use of high centrifugal force I have accomplished what has been considered throughout the sugar industry as impossible, to wit, actual separation of adhering syrup from sugar crystals without washing. I have accomplished this even though centrifuging takes place at relatively low temperatures, that is, below temperatures of 50° to 60° C., at which centrifuging has taken place heretofore, particularly when syrups of low purity were discharged.

I have found that the degree to which syrup is discharged from the crystals is not directly proportional to the centrifugal force employed, but that at certain centrifugal forces in excess of those used prior to my invention there are large increases in the degree to which the syrup is discharged. Furthermore I have found that the syrup discharged does not act as a homogeneous whole as has been heretofore supposed, but that its composition differs at various centrifugal forces up to the maximum necessary to effect complete separation. Analyses of the discharged syrup at various centrifugal forces show that various constituents of the syrup

separate from the crystals at different centrifugal forces and that each constituent has a different critical point at which a substantial let go takes place, that is, the degree to which the particular constituent is separated from the crystal is considerably increased. 70

For instance, in the neighborhood of a certain centrifugal force depending on the characteristics of the sugar and syrup under treatment, there is a large increase in the amount of organic matter thrown off. At a different centrifugal force the same is true of the ash as well as other constituents. By this means, therefore, it is possible to reduce the proportion of a particular constituent in the discharged syrup by collecting in a separate container the syrup thrown off at the critical let-go point for that constituent. On the other hand the proportion of the particular constituent in the syrup collected in the separate container is relatively high. It is, of course, understood that a separate container may be used at any number or all critical points if desired. By this means a graduated separation of the constituents of the adhering syrup is made possible. 80

A graduated separation of the syrup into portions having a relatively high proportion of a particular constituent is of value for instance in the processes for the extraction of further sugar from the molasses. The proportions of organic, saline, or other impurities which prevent crystallization of the sugar in the molasses may be reduced in this manner, or the proportion of the particular impurity having the greatest effect upon crystallization may be reduced. 90

The phenomena of surface adherence between syrup and crystal are not a mere matter of surface tension or of capillary attraction in the interstices formed by the crystals, but involve adsorption and possibly other phenomena. 100

The crystals are not crushed or deformed by the centrifugal forces employed and, although the total space between the crystals decreases somewhat, a point is finally reached beyond which no further decrease takes place and at which the syrup can still be effectively removed from the crystals. 110

It is understood that the term "raw sugar" as used herein includes not only first, second and third sugars but any type of sugar having adhering particles, and whether raw, refined, or otherwise. 115

Having described my invention, it is obvious that many modifications may be made in the same such as the adding, eliminating or changing the order of or varying the degree of certain steps in the process; using any other gas in place of air; moistening with any other solvent for the sugar; applying the invention to the crystallization of other products in which case the air or other gas may be saturated or partially saturated with water, 120

or any other solvent desired, etc.; using other devices in place of centrifugals employing for instance linear, transverse, circuitous or reciprocatory motion; moistening or desiccating beyond the desired point and then returning to such point; using temperatures above or below those for which calculations have been made; moistening or desiccating at certain rates, or variety of rates, and at certain, or a variety of, temperatures, above or below the final temperature; etc. etc. without departing from the spirit of the invention. Reference is made to my copending generic application, Serial Number 167,597, filed February 11, 1927 which has resulted in Patent No. 1,809,807.

I claim:

1. The process of reducing the sugar content of dried syrup adhering to sugar crystals in raw sugar comprising placing said sugar in an enclosure, moistening said syrup to bring it to a fluid-like state and regulating the temperature and moisture content of said syrup to reduce the sugar content thereof by crystallization, and then removing the syrup from the sugar crystals.

2. The process of reducing the sugar content of dried syrup adhering to sugar crystals in raw sugar comprising placing said sugar in an enclosure, moistening said syrup to bring it to a fluid-like state and regulating the temperature and moisture content thereof by regulating the temperature and moisture content of the air in said enclosure to reduce the sugar content of the syrup by crystallization, and then removing the syrup from the sugar crystals.

3. The process of reducing the sugar content of dried syrup adhering to sugar crystals in raw sugar comprising placing said sugar in an enclosure, moistening said syrup to bring it to a fluid-like state, and regulating the moisture content thereof to reduce the sugar content of the syrup by crystallization, and then removing the syrup from the sugar crystals.

4. The process of reducing the sugar content of dried syrup adhering to sugar crystals in raw sugar comprising placing said sugar in an enclosure, moistening said syrup to bring it to a fluid-like state and regulating the moisture content thereof by regulating the moisture content of the air in said enclosure to reduce the sugar content of the syrup by crystallization, and then removing the syrup from the sugar crystals.

5. The process of reducing the sugar content of dried syrup adhering to sugar crystals in raw sugar comprising placing said sugar in an enclosure, moistening said syrup to bring it to a fluid-like state and regulating the temperature and moisture content of said syrup to reduce the sugar content thereof by crystallization, and then removing the syrup from the sugar crystals by the use of a cen-

trifugal force sufficiently high to overcome the adherence of substantially all of the syrup to the sugar crystals.

6. The process of reducing the sugar content of dried syrup adhering to sugar crystals in raw sugar comprising placing said sugar in an enclosure, moistening said syrup to bring it to a fluid-like state and regulating the temperature and moisture content thereof by regulating the temperature and moisture content of the air in said enclosure to reduce the sugar content of the syrup by crystallization, and then removing the syrup from the sugar crystals by the use of a centrifugal force sufficiently high to overcome the adherence of substantially all of the syrup to the sugar crystals.

7. The process of reducing the sugar content of dried syrup adhering to sugar crystals in raw sugar comprising placing said sugar in an enclosure, moistening said syrup to bring it to a fluid-like state, and regulating the moisture content thereof to reduce the sugar content of the syrup by crystallization, and then removing the syrup from the sugar crystals by the use of a centrifugal force sufficiently high to overcome the adherence of substantially all of the syrup to the sugar crystals.

8. The process of reducing the sugar content of dried syrup adhering to sugar crystals in raw sugar comprising placing said sugar in an enclosure, moistening said syrup to bring it to a fluid-like state and regulating the moisture content thereof by regulating the moisture content of the air in said enclosure to reduce the sugar content of the syrup by crystallization, and then removing the syrup from the sugar crystals by the use of a centrifugal force sufficiently high to overcome the adherence of substantially all of the syrup to the sugar crystals.

In testimony whereof, I have signed my name to this specification this fifth day of March 1930.

JULIEN BERGÉ.
